ABSTRACT OF THE DISCLOSURE

A metal article is marked for identification by fusing to its surface a nugget of a second metal which contrasts with the metal of the article.

This invention relates to the marking of metal articles for identification purposes. It is more particularly concerned with fusion marking a metal article during its processing so as to permit its later identification.

In the manufacture of metal articles such as sheets, tubes, rods, shapes and the like, it is frequently desirable to mark the article during its manufacture so that the article can be later identified. For example, it is often desirable to mark an article coming out of a heating furnace or from a rolling mill so that it can be identified from other like articles after the articles have been collected, or after they have undergone further processing. Where successive articles are made from a single billet, bloom, ingot or other unit of starting material, such a marking serves to identify the beginning or end of the unit of starting material so as to distinguish its product from that of the next unit of starting material. Where successive articles are inspected at an intermediate stage of their manufacture it is sometimes more convenient to segregate the marked articles from the unmarked articles at a later stage of their manufacture or handling.

It is difficult to mark satisfactorily articles which scale on heating. Surface scale, in subsequent handling of the article, falls off partially or wholly, carrying with it markings which do not penetrate below the scale. Markings which indent the surface of the article provide notches for stress concentrations which can lead to premature failure of the article in service. The problem is particularly acute in the rolling of steel into finished products because of the high temperatures at which steel is processed, but it also exists in the marking of articles of other metals.

It is an object of my invention, therefore, to provide a process of marking a metal article so that later it can be positively identified, and to provide articles so marked. It is another object to provide such a process applicable to articles heated to high temperatures. It is another object to provide such a process applicable to articles with scaled surfaces. It is another object to provide such a process permitting automatic identification of the marked articles. It is another object to provide such a process which is not detrimental to the service life of the marked article. Other objects will appear in the course of the description of my invention which follows.

I have found that a metal article, heated or otherwise, can be provided with an identifying mark which is later distinguishable by fusing to its surface a nugget of a contrasting metal. By "nugget" I mean a small mass of a size such that its exposed portion consists of the contrasting metal. The nugget need not be raised above the steel surface to any considerable extent. By "contrasting metal" I mean a metal which is visually distinguishable from the metal of the article, such as by color, or which can be readily distinguished because it has a property different from those of the metal of the article. Visually distinguishable metals are copper and steel, for example.

2

Metals distinguishable by their properties are magnetizable and nonmagnetizable metals, for example.

I prefer to fuse the nugget to the metal article by bringing the article into contact with an electrode of the marking metal and passing an arc welding current from electrode to article. Apparatus suitable for the practice of the presently preferred embodiment of my invention is shown schematically in the attached figures, to which reference is now made.

FIGURE 1 is a schematic elevation of apparatus suitable for the practice of my invention. FIGURE 2 is a plan of a portion of an article of my invention so marked.

The article 1 to be marked, shown as a length of pipe, is supported for travel on a conveyor or run-out table, not shown. If the article is hot or has been heated, its surface is covered with scale 8. The conveyor or run-out table is made of a conductor so that through it article 1 is electrically connected to ground 2. One terminal of a current supply 3 which is conventionally a welding generator is also connected to ground 2. The other terminal 4 of current supply 3 is connected to electrode material 6 fed from electrode supply means 5. These means 5 are insulated from ground and are adapted to feed electrode 6 in the form of a rod or wire toward article 1 as is required. Electrode 6 is made of a metal which contrasts with the metal of the article 1 as I have described. Current supply 3 is provided with control means, not shown, to provide pulses of current as they are required.

In my process electrode 6 is advanced by electrode supply means 5 into contact with the surface of article 1. The latter need not be stationary but can maintain contact with electrode 6 as article 1 moves along its run-out table. When article 1 is to be marked, a pulse of welding current is caused to pass through electrode 6 and article 1 from current supply 3 to ground 2. That current forms a momentary arc between electrode 6 and article 1 which fuses a portion of the end of electrode 6 to article 1 as a nugget of metal 7. The presence of scale 8 which is relatively nonconducting does not interfere with my process. Current supply 3 is adjusted to provide an arc which penetrates scale 8 between electrode 6 and article 1. The nugget 7 of electrode 6 fuses or welds to article 1 and to some extent alloys with it. If too hot an arc is struck, all the metal of nugget 7 will alloy with that of article 1, and contrast will be lost. The arc must be adjusted so that at least the surface of nugget 7 does not alloy with the metal of article 1. If the arc is not hot enough, it does not penetrate the scale, and the nugget deposited is not welded to the underlying metal.

The nugget of metal 7 so deposited is visually distinguishable even though article 1 undergoes further processing when the metal of electrode 6 is of a different color from that of article 1. As I have mentioned, a nugget 7 of copper on a steel article 1 distinguishes it from other steel articles not so marked. A nugget of aluminum also distinguishes a steel article to which it is applied from other steel articles not so marked although the contrast is not as great as between steel and copper.

A nugget of aluminum on a copper article visually distinguishes it from other copper articles, and conversely a nugget of copper on an aluminum article distinguishes it from other aluminum articles. Other combinations of metals suitable for my invention will suggest themselves to those skilled in the art.

Articles of nonmagnetizable metal are conveniently marked for automatic detection by welding thereon a nugget 7 of magnetizable metal such as iron or steel. When the marked articles are to be separated from the unmarked articles, all are moved successively past magnetizing means and then past a search coil, in which signals are generated by the nuggets of magnetized metal.

In the marking of steel articles I have used a copper electrode of $\frac{3}{16}$ " to $\frac{1}{4}$ " diameter and a welding current of 40 to 60 amperes with entire satisfaction. The nugget 7 so deposited is not large and does not protrude appreciably above the metal surface. The nugget does not provide a locus for stress concentration, nor are the properties of the article injured by the relatively small amount of heat generated in its deposition, nor in any other way.

I claim:

1. In the manufacture of metal articles, including the steps of heating the articles to temperatures at which scale forms on their surfaces, marking selected articles, further processing the articles so that the surface scale is caused to fall off, and then classifying the articles in accordance with the presence or absence of those markings, the improvement comprising marking an article by making contact between the article and an electrode of a metal contrasting with the metal of the article and passing through the electrode, scale, and the article a

welding current adapted and adjusted to weld a nugget of electrode metal to the article so that it is not dislodged by further processing without alloying the outer surface of the nugget with the metal of the article.

2. The method of claim 1 in which the contrast is between magnetizable metal of the electrode and nonmagnetizable metal of the article.

3. The method of claim 1 in which the contrast is of color.
